UNITED STATES PATENT OFFICE.

WILLIAM A. HUTSON, OF KANSAS CITY, MISSOURI, ASSIGNEE OF ONE-HALF TO
WILLIAM M. FREEMAN, OF PAULS VALLEY, OKLAHOMA.

FLYING-MACHINE.

1,087,946.

Specification of Letters Patent.

Patented Feb. 24, 1914.

Application filed May 15, 1913. Serial No. 767,852.

To all whom it may concern:

Be it known that I, WILLIAM A. HUTSON, citizen of the United States, residing at Kansas City, in the county of Jackson and State of Missouri, have invented certain new and useful Improvements in Flying-Machines, of which the following is a specification, reference being had to the accompanying drawings.

10 This invention relates to flying machines and more particularly to a machine of that type commonly known in the art as "dirigible", the invention having for its primary object to provide improved means for preventing heating and undue expansion of the gas through the medium of which the desired buoyancy in machines of this character is obtained.

The invention has for another object the provision of improved propellers arranged upon opposite sides of the machine whereby a maximum of air is displaced and the speed of movement of the machine materially accelerated, and means for independently controlling and positioning said propellers with respect to the body of the machine.

Another and more specific object of the invention resides in the provision of a skeleton wheel including retaining means for independently inflatable and removable sections or compartments, and means for constantly rotating said wheel to prevent overheating of the gas contained in said compartments and to reduce air resistance to a minimum.

It is a further object of my invention to provide side propellers, front and rear rudders, and a central rotatably mounted wheel provided with removable inflatable bags, primary operating means, and means for independently connecting the propellers and rudders to said operating means to be actuated thereby or disconnecting the same from the operating means for operation by the natural air currents.

The invention further comprehends the provision in a machine of this character of means for obtaining a maximum of buoyancy with a minimum of air resisting surface, and to so construct the machine that the same will be light in weight, and may be easily and quickly repaired at a nominal cost.

With the above and other objects in view it will become apparent as the description

proceeds, the invention consists in certain constructions, combinations and arrangements of the parts that I shall hereinafter fully describe and claim.

For a full understanding of the invention, reference is to be had to the following description and accompanying drawings, in which—

Figure 1 is a side elevation of a flying machine embodying the present invention; Fig. 2 is an end elevation thereof; Fig. 3 is an enlarged side elevation of one of the rudders, Fig. 4 is a section taken on the line 4—4 of Fig. 3; Fig. 5 is an enlarged detail view illustrating the operating and controlling means for the rudders and propellers; Fig. 6 is a detail view showing the gearing for operating the main wheel which carries the inflatable gas compartments. Fig. 7 is a detail section taken on the line 7—7 of Fig. 5; Fig. 8 is a detail perspective view of one of the removable gas bags or compartments.

Referring in detail to the drawings, 5 designates the body frame of the machine, 80 preferably, though not necessarily, constructed of aluminum, which may be braced in any approved manner. This frame is centrally provided with an operator's platform 6 and beneath each end of the frame, 85 the wheels 7 are mounted. It will of course be obvious that if desired, in place of the wheels, the usual skids or runners may be used.

8 designates the upper longitudinal bars 90 of the frame structure in which the ends of a centrally arranged transverse shaft 9 are fixed. Upon this shaft the hollow tubular hub 10 of a wheel is mounted to rotate, bearing balls or other suitable anti-friction 95 means being arranged between said hub and the shaft. The wheel structure embodies an annular rim 11. Oppositely inclined skeleton side frames 12 connect this rim to the ends of the tubular shaft 10. 100 These skeleton frames may be of any approved form or construction and between the same the inflatable gas bag sections 13 are adapted to be arranged. Each of these sections is of substantially quadrant form as 105 shown in Fig. 8, and when in its collapsed condition, may be readily disposed between the skeleton side frames 12 of the wheel. Each of the gas bag sections is provided with a suitable inflating valve 14 to which one end 110

of a rubber tube or hose is connected, the other end of said tube being attached to a valve of one of a pair of gas containing tanks indicated at 15 which are mounted in the machine frame. The rim 11 of the wheel 5 is provided with a peripheral groove 16 to receive a cable 17. This cable extends around guide pulleys 18 mounted in hanger brackets depending from the platform 6. 10 A shaft 19 is also mounted beneath said platform having a pulley 20 fixed thereon over which the cable 17 extends. A gear wheel 21 is fixed upon said shaft with which a gear wheel 22 on the lower end of the vertical shaft 23 meshes. Through the medium of these intermeshing gears, it will be obvious that the gas bag carrying wheel may be rotated. The shaft 23 is driven by means of an engine or other prime mover 24 which 15 may be of any approved form, a beveled pinion 25 on the engine shaft meshing with a beveled gear 26 upon the vertical shaft 23. The pinion 25 is keyed for sliding movement upon the engine shaft and may be shifted 20 into or out of engagement with the gear 26 by means of the lever 27.

In each side of the main frame 5, centrally thereof, provision is made for the main driving propeller. Each of these propellers consists of a hollow elliptical body 28 which is provided with longitudinally extending spindles or stub shafts 29 at its opposite ends. The major axis of the hollow propeller member 28 is disposed vertically 35 of the body of the machine and the spindle 29 on the upper end thereof is mounted to rotate in a depending hanger bearing 30 which is fixed to the longitudinal bar 8 of the machine frame. The spindle 29 on 40 the lower end of said propeller member is seated in a step bearing 31 which is suitably mounted in the frame 5.

32 designates a curved frame member which extends in substantially concentric 45 relation to the hollow propeller member 28, and at its ends, is loosely engaged upon the terminal spindles 29 of said member. In the frame 32, centrally thereof a fan blade propeller 33 is mounted. A pinion 34 upon 50 the shaft of said propeller meshes with the pinion 35 fixed to the vertical shaft 36 which is arranged in the frame member 32. The lower end of this shaft is mounted in a bearing arm 37 projecting from the lower 55 end of said frame member. The shaft 36 is provided with a sprocket wheel which is traversed by an endless chain 38, said chain extending around a similar sprocket wheel on the lower spindle 29 of the propeller 60 member 28. The elliptical propeller member 28 is provided with longitudinally extending peripheral vanes or blades 39 which are widest at the center of said member and gradually taper to the ends thereof. To 65 the lower end of the frame member 32 in

which the propeller 33 is mounted, a peripherally grooved wheel 40 is fixed. Around this wheel one end of a cord or cable 41 passes, said cable extending over a suitable guide pulley 42 and around a drum 70 43 mounted to rotate upon the supporting shaft 44. The drum 43 is provided upon one end with a suitable hand wheel 45 whereby the same may be conveniently rotated to swing the fan propeller 33 and position 75 the same with relation to the main propelling member 28, as will be understood.

As above stated, one of the driving propellers such as above described is mounted in each side of the machine frame 80 and these propellers may be independently driven by means of the endless driving chains 46 which connect the sprocket wheel upon the lower spindle of each of the propelling members 28 to similar sprocket 85 wheels loosely mounted upon the upper end of the vertical shaft 23. At each end of the main frame 5, a pair of looped bars 47 are arranged, said bars being disposed in parallel relation and having their ends integrally 90 connected, and formed with the arms 48 which are mounted to rotate in bearing members 49 provided upon the main frame 5. The looped rods or bars 47 are vertically 95 disposed and the depending arms 48 thereof are hollow to receive the upper ends of the vertical shafts 50, the lower ends of which are connected by means of the sprocket chains 51 to the main driving shaft 23. In the parallel looped bars 47 and connecting 100 the same a stationary shaft 52 is arranged. A beveled gear 53 is rotatably mounted upon said shaft. This gear engages a pinion 54 fixed upon the propeller shaft 55 which is mounted in bearings 56 provided upon the side of a disk or wheel 57 loosely arranged upon the shaft 52.

58 designates the fan blade propeller which is fixed upon one end of the shaft 55. A rope or cable 59 traverses the wheel 57 and 110 extends around suitable guide pulleys 60 to a drum 61 which is mounted and operated in a similar manner to the drum 43. Upon one of the looped bars 47, a sheet of canvas, rubber or other material indicated at 75 is 115 secured. This flexible sheet acts as a rudder vane in the steering of the machine as will be later described. The gear wheel 53 is driven through the medium of a pinion 62 fixed upon a shaft 63 which is mounted in 120 the bars 47, said shaft being driven by the endless chain 64 which traverses a sprocket thereon and a similar sprocket on the upper end of the shaft 50. The ends of a cord or cable 65 are connected to the intermediate 125 portions of the looped bars 47, said cable passing around a drum 66 mounted on the shaft 44. Each of the drums on this shaft is provided with a brake band 67 normally held in frictional engagement therewith by 130

means of a coil spring 68. A foot lever 69 is connected to said brake band whereby the drum may be released at the will of the operator.

- 5 It will be seen from the above that the control of the machine is by means of six drums, three of which operate corresponding parts to those controlled by the other three on the opposite side of the machine.
- 10 Each of the rotary propelling members 28 is also provided at its lower end with a disk 70 for engagement by a brake lever 71 which is actuated by the operator through the medium of a cord or cable 72.
- 15 Each of the loose sprockets on the upper end of the shaft 23 which is traversed by the sprocket chains 46 or 51 is adapted to be locked on said shaft by means of a sliding clutch member 73 actuated by the operator by means of a lever 74 fulcrumed intermediate of its ends upon the frame structure.
- 20 From the foregoing description, the construction and manner of operation of my improved flying machine will be clearly understood. The inflatable bags or compartments 13 are arranged in the skeleton wheel and are properly inflated, the side frames of said wheel preventing undue expansion of the bags and retaining the same in place. These bags give the required buoyancy to the machine so that it will rise from the ground. The front and rear propellers as well as the side propellers may be driven by shifting the clutch members 73 and engaging the pinion 25 on the engine shaft with the gear wheel 26 on the driving shaft 23. The wheel in which the inflatable compartments are arranged is continuously rotated during the operation of the machine and owing to the diamond shaped cross-sectional form of the wheel, it will be obvious that but little resistance is offered thereby to the forward movement of the machine, while the heating of the gas which would be caused by friction incident to such resistance is obviated. Thus liability of the explosion of the gas contained in the bags or compartments is eliminated. The wheel rotates forwardly or in the direction of flight of the machine as indicated by the arrow in Fig. 1, while the backwardly driven air from the forward propeller 58 cools the walls of the gas bags or compartments as they are successively brought to a forward position. This large rotating wheel also forces the air downwardly during the forward movement of the machine and occasions a lifting impulse. By mounting the inflatable bags in a rotatable wheel in the manner above disclosed, anyone of said bags may be easily removed by the operator from his position in the machine or resupplied with gas when necessary. It will further be obvious that as the side propellers 33 are driven, the air engaging the vanes or blades of the elliptical pro-

pelling member 28 is distributed over a comparatively wide area and a large amount of air is displaced thereby. This air is directed toward the inflatable bag sections mounted in the rotatable wheel and further serves to cool the same as well as giving an upward impulse to the body of the machine owing to the fact that the propelling members are located below the axis of the bag carrying wheel. When it is desired to change the course of the machine, the operator may swing either of the propellers 33 by means of the cables 41 and thereby cause the machine to move laterally, said propellers 33 assisting the front and rear propellers in effecting a quick turning movement. In order to raise or lower the machine, the operator rotates the drums 61 to change the position of the propellers 58 to direct the forward end of the machine upwardly or downwardly, as the case may be. The machine is of course moved through a circular path or turned by operating the drums 66 to which the cables 65 are connected. When the natural air currents are of sufficient strength, the clutches 73 may be shifted to disconnect the driving chains from the shaft 23. The extensive air contacting surface of the blades or vanes of the main side propellers 28 against which the air is driven by the fan propellers 33 will be sufficient to maintain the machine in flight. Thus the operating power may be conserved.

From the foregoing, it is believed that the construction and several advantages of my machine will be clearly understood.

The invention is comparatively simple in its construction, light in weight and may be easily and safely operated. The provision of the independently removable inflatable bags or compartments greatly reduces expense incident to repair of the machine, as these bags may be easily and quickly removed when torn or otherwise unfit for use and new ones provided at comparatively small cost. The several bag sections are securely retained in position within the wheel and in cases of emergency, anyone of said bags may be easily and quickly reached by the operator, and repaired or replaced.

It is of course obvious that my machine is capable of a great many modifications in the form, proportion and construction of the several parts thereof and I therefore reserve the right to resort to all such legitimate modifications as may be fairly embodied in the spirit and scope of the appended claims.

Having thus described the invention, what is claimed is:

1. In a machine of the character described, a rotatable frame, a plurality of inflatable compartments removably mounted in said frame, side propellers, front and rear propellers, a common operating means therefor, and means for independently connecting or

disconnecting the several propellers and said operating means.

2. In a machine of the character described, a rotatable frame having side walls converging from the axis to the periphery thereof, a plurality of removable inflatable gas compartments mounted in said frame, propellers arranged upon each side of said frame and below the rotative axis thereof, operating means, and driving means for the propellers connectible at will to the operating means.

3. In a machine of the character described, a rotatable wheel having skeleton side walls, and a plurality of inflatable compartments arranged between said side walls and independently removable therefrom.

4. In a machine of the character described, a rotatable wheel embodying an axis, a rim, skeleton side walls converging from the ends of the wheel axis to said rim, and a plurality of inflatable compartments arranged between said side walls and independently removable from the wheel.

5. In a machine of the character described, a series of independently inflatable compartments movable through a circular path from a common center, an elliptical propelling member rotatably mounted upon each side of said series of compartments, additional propellers mounted for swinging movement with relation to said members and disposed contiguous thereto, means for swinging said latter propellers, driving con-

nctions between said propellers, operating means, and a driving connection between said operating means and the first named propelling members.

6. In a machine of the character described, a rotatable wheel provided with a plurality of inflatable compartments, elliptical propelling members arranged below the axis of the wheel at either side of the machine, said members having their axes vertically disposed, front and rear propellers, a common operating means for said latter propellers, the elliptical propellers and said wheel, and means for independently connecting or disconnecting the several propellers and the wheel to said operating means.

7. In a machine of the character described, a rotatable frame, a plurality of inflatable compartments removably mounted in said frame, elliptical side propellers having vertical axes, a frame mounted for swinging movement upon the axis of each propeller, additional propellers and operating means therefor carried by said frames, a primary operating means for said wheel, and means for connecting or disconnecting said propellers and the primary operating means.

In testimony whereof I hereunto affix my signature in the presence of two witnesses.

WILLIAM A. HUTSON.
